(57) **CLAIM**

The ornamental design for a storage device, as shown and described herein.

DESCRIPTION

FIG. 1 is a perspective view of the storage device of the present design;

FIG. 2 is a front view of the storage device shown in FIG. 1;

FIG. 3 is a side view of the storage device shown in FIG. 1; FIG. 4 is a top view of the storage device shown in FIG. 1; FIG. 5 is a perspective view of the storage device shown in FIG. 1 with a pocket knife;

FIG. 6 is a front view of the storage device shown in FIG. 1 with a pocket knife; and,

FIG. 7 is a side view of the storage device shown in FIG. 1 with a pocket knife.

The long dash-dot broken lines shown in FIG. 4 and also in FIG. 1 depict portions of the storage device that form no part of the claimed design. The dash-dot broken lines in FIGS. 5-7 showing a pocket knife depict environmental subject matter that forms no part of the claimed design.
